UNITED STATES PATENT OFFICE.

WINSLOW W. DUNN, JR., AND CLAIRE I. WEIKERT, OF ST. PAUL, MINNESOTA; SAID DUNN ASSIGNOR TO SAID WEIKERT.

SHIPPING CASE.

Application filed May 19, 1925. Serial No. 31,435.

This invention relates to shipping cases, and especially to cases adapted for utilization in the shipment of containers filled with perishable commodities.

5 The invention has great utility in connection with the shipment or transportation of containers for ice cream or milk, where it is not only necessary to insulate the container from the relatively warm outside atmosphere, but also to protect the container from injury during transportation.

10 The object of the invention therefore is the provision of shipping cases of the character above referred to, which will not only tend to preserve the temperature and condition of the commodity within the container, but will also protect the latter from injury.

15 A further object of the invention is the provision of a case of the class described which is so constructed as to endure under the relatively hard usages to which it will be subjected during transportation, and which is equipped with instrumentalities which not only facilitate handling, but which 20 insure that the case will be so handled, during transportation, as to minimize the danger of undue wear upon the case, or damage to the contents thereof.

25 Other objects of the invention will be made apparent in the following specifications, taken in connection with the drawings forming a part thereof.

In said drawings:

30 Fig. 1 is a longitudinal vertical section taken centrally through a case constructed in accordance with our invention.

35 Fig. 2 is a reduced perspective view showing the method of carrying a case, during transportation.

40 Fig. 3 is a perspective view of a case ready for shipment.

Fig. 4 is a perspective view of the outer section of the case.

45 Fig. 5 is a fragmentary perspective view, showing the inner section of the case applied to a container for ice cream, milk, or other perishable product.

Fig. 6 is a transverse section taken through Fig. 1, and,

50 Fig. 7 is an enlarged fragmentary section of the corner of the outer section of the case shown in Fig. 1.

Now referring specifically to the drawings, in which similar reference characters

55 indicate like parts throughout the several views, the case comprises an inner tubular member A, closed at the bottom, and an outer tubular member B closed at the top, and adapted to telescope over the member A with a close fit. The member A is formed 60 to receive and closely embrace a container C, adapted to receive ice cream, milk, or any other commodity. It is to be understood that the case may be made in several types as to size and configuration, whereby 65 to adapt it for use in receiving standard containers of as many varying types.

Both members A and B, are provided with enclosing walls of exactly the same material, but of slightly different dimensions whereby to adapt the member B to fit over the member A. Both members are preferably provided with side walls 1, comprising an inner section 2 of insulating material of a thickness of approximately 75 $\frac{1}{2}$ inch, and of sufficient inherent rigidity to cause the case to retain an upright position when not in use. An insulating material such as flax-li-num is preferred, although balsam wool, or other materials 80 possessed of the necessary insulating characteristics, may be used. The end walls, that is the bottom of the section A, and the top of the section B, are also provided with the insulating section 2.

85 In the preparation of the case, the side walls 1 of each section are prepared and cut to the desired size and rolled to tubular form, the two edges being connected to retain the tubular formation. The wall 1 is then entirely covered, on the outside, by a heavy water-proof and mildew-proof canvas 3, and on the inside by a salt resistant canvas 3', and the two sections 3 and 3' are secured to the material 2 by a plurality of 90 rows of stitching 4, 4, the canvas layers being so applied as to leave a peripherally extending canvas rim 5 at the top of the section A and at the bottom of the section B, and the rim 5 is also traversed by a row 100 of stitching 6, to retain the insulation 2.

The bottom 7 of the section A is formed exactly as is the top of the section B, and hence a description of an end of one section is sufficient. As clearly shown in Fig. 1, and more specifically in Fig. 7, the top 8 of the outer section B is provided with two disk-shaped layers of the selected insulating ma-

- terial 8' and 8'', positioned concentrically, the smaller disk 8'' lying below the larger disk 8'. Each of the disks 8' and 8'' is of the thickness of the insulating sections 2 of the walls. The disks 8' and 8'' are held between an inner lining 9, which may be of the same material as the salt resistant canvas 3', and which extends downwardly over the outside of the section 10 B, and an outer covering 10, of the same material as the canvas 3 heretofore referred to, a plurality of rows of stitching extending through the cover, disks and lining, and permanently securing them together. To the 15 outer periphery of the covering 10 is stitched a slip 10', which extends downwardly along the side walls 1 of the section B, and which is secured to said wall by one of the rows of stitching 4, along the lower edge of the slip. 20 To obtain additional insulation and rigidity at the top, the lining 3' is also extended over the top periphery of the section 2, and downwardly along the outer wall 1, terminating flush with the lower edge of the slip 10', so 25 that the rows of stitching 4 extend through the slip 10', the lining 9, the lining 3', the covering 3, the insulation 2, and again through the lining 3'. Suitable stitching may be provided as desired, to provide for 30 durability and strength, or for increased insulation. As hereinbefore stated, the bottom of the inner section A is formed exactly as is the top of the section B, as just described, it being noted that the insulating 35 sections 12 and 12' are each of the same thickness as the section 2, and that a slip 13 is stitched to the end cover 14, of the section A.
- It is also to be noted, as shown in Figs. 1 40 and 7, that, because of the smaller diameter of the disk 8'', and 12, with respect to the diameter of the disks 8' and 12', a circular seat is formed for the side walls of each section, whereby to provide additional insulation 45 at the ends of the case, an advantage to be hereinafter discussed. It is also to be observed that the slips 10' and 13 are secured to the outer peripheries of the disks 8' and 12', respectively, and that said slips 50 extend over the joints between said disks and are secured in such position, whereby to prevent access of air through said joints. 55 The rim 5 at the top of the section A is separated at diametrically opposed points, to receive the ends of strap members 15, 15', one of which carries a buckle or fastening element 16, adapted to receive the free end of the other strap, and the straps being secured by stitching to the rim, as will be understood without further explanation. Also, the bottom of the member A carries a strap 17, secured by a row of stitches 18, to the cover of the lower end of the section A, the strap 17 having free ends 17', adapted for detachable connection to co-operating fas-
- 70 A handle 20, is secured to the outside of the member B, and comprises a strip 21 of very strong webbing which diverges diagonally and downwardly along the sides of the member B, being secured to the member by the rows 4 of stitching, and by other rows of stitching extending longitudinally of and on both sides of the strip 21. The handle 75 portion 20 of the strip 21 is free to move laterally of the member B, and is positioned at a point above the axial center thereof. 80 In order to guard against any circulation of air between the sections A and B, when 85 in telescoped condition, I provide an apron 22 which is secured to the outside of the section A by one of the rows 4 of stitching. The apron is secured in the position shown in Figs. 1 and 5, creating a slight bulge at 90 the point of juncture, and its lower circular portion is of greater diameter than the outer diameter of the section A. Therefore, as the section B is forced downwardly over the section A the material of the apron is 95 squeezed between the two sections, forming practically an air-tight seal which prevents the passage of any air between the lower edge of the section B, and upwardly along the sides of the section A. Such compression causes a slight protuberance in the section B, greatly exaggerated in Fig. 1 of the drawing, but not noticeable in the actual product. 100
- In operation the container C is seated 100 within the member A, as indicated in Fig. 5, it being noted that the upper end of the container projects very slightly above the top edge of the member. The lids of all such containers are usually provided with a handle 23, as indicated, and the straps 15, 15' are extended beneath said handle and tightly secured each to each, thereby not only preventing dislodgment of the handle, but also securing the member A to the container C. 105 Furthermore, as the straps 15 and 15' are tightened, they contact the top of the closure D, pressing it tightly against its seat and preventing it from becoming released during transportation. 110
- The member B is then telescopically fitted over the member A, and the strap ends 17' engaged with the co-operating elements 19, to draw the members longitudinally of one another until they are in very close contact 115 120 each to each at the ends, and the case is transported in this condition. 125
- It will be noted that the insulation at the ends of the assembled case is of the same thickness as that of the sides. The double insulation at the ends of the sections A and B is of great importance, especially in the shipment of ice cream or milk. The containers are always stood upon end and, in a great many instances, the upper end is ex- 130

- posed to the rays of the sun, the double insulation under such circumstances serving to effectively preserve the temperature of the commodity contained in the ends of the cans.
- 5 In the ice cream trade the retailer is satisfied if, during shipment, the temperature is substantially maintained in the top end of the container, because the goods are naturally first vended from that end, the general 70 custom of retailers being to refrigerate the cans immediately upon receipt, in order to remove from the main body of the cream the excess heat units accumulated during transportation. Consequently, if the proper temperature is preserved in the top of the container, the cream may be vended therefrom while the temperature of the main body is being properly reduced.
- 10 The bottom of the inner member A is also provided with the double insulation, since it is usually seated upon the relatively warm floor of a car during shipment, or is allowed to stand upon the sun-heated platforms of stations after being removed from the transporting vehicle. The double insulation therefore effectively protects the commodity in the bottom of the container from the deleterious effects of absorbed heat, and the consequent softening of the cream in said 25 bottom.
- 15 In removing the cases from the car, wagon or other transporting vehicle, the operator finds it most convenient to grasp the handle 20. The handle 20 is so disposed relatively 30 of the length of the case, that, when the operator's arm is extended naturally to carry the case, the bottom of the latter will not reach the ground. If the operating handle were positioned at the top of the member B, 35 practically all operators would drag the case over the floor of the car, or over the ground, in delivering it to its destination, resulting in unnecessary wear on the bottom thereof. By practically forcing the operator to grasp 40 a handle located at the side of the case, the bottom of the case frees the floor or ground, as illustrated in Fig. 2, and prevents unnecessary wear.
- 45 From the foregoing it will be obvious that the invention covers a shipping case which affords a double insulation throughout, which insulation is increased at each end, thereby preserving the temperature of the goods carried by the container C. With such cases properly constructed and insulated with the materials referred to, or with others as efficacious, it is practically impossible for any outside air to reach the interior of the case, and the temperature of ice cream 50 in the container will maintain for 24 or 36 hours.
- 55 The inner canvas which is applied to the members A and B is a mildew-proof material known on the market as "Shuredry". Furthermore the outer canvas is formed of 60 an article known as "Preservo" which is absolutely waterproof, the result being that, if the cases are exposed to the elements, no water will soak through and rust the containers C, and the case will not become mildewed. 70
- 65 Also, because of the "Preservo" treated canvas and the "Shuredry" lining, the case is resistant to the erosive action of salt which is generally used in packing ice cream for 75 shipment.
- 75 The article referred to is essentially a one-man case, since it is of course easy for one operator to place the top section B over the bottom section A. In removing the top section B the straps 17' are released from the fasteners 19, and laid flat on the floor which supports the case. As shown in Fig. 80 5, the operator then straddles the can and places a foot on each of the flat straps 17' and pulls the outer section B from off the inner section A, as will be understood.
- 85 Modifications of the structure herein described will be suggested to those skilled in the art, but the invention covers all modifications fairly falling within the appended 90 claims.
- 95 What we claim is:
1. A shipping case comprising telescoping members, and an end closure for each member, each end closure being of an insulating efficiency equal to double the insulating efficiency of the side walls of the members.
  2. A shipping case comprising two telescoping members each having side walls containing a thickness of insulating material, and with an end wall having an insulating efficiency double that of the side walls.
  3. A shipping case comprising two telescoping members of insulating material, the outer member being entirely covered with water-proof and mildew-proof material, and the inner member being lined with salt resistant material, each member having an end closure possessed of an insulating efficiency double that of the body portion of the member.
  4. A shipping case comprising two tubular members formed of insulating material, one adapted to telescope over the other, each member being made up of a cylindrically formed side wall, and an end closure consisting of two superposed insulating disks of different diameters, whereby to provide a socket shaped to receive the peripheral edge of said side wall.
  5. A shipping case comprising two tubular members formed of insulating material, one adapted to telescope over the other, each member being made up of a cylindrically formed side wall, and an end closure consisting of two superposed insulating disks of different diameters, whereby to provide a socket shaped to receive the peripheral edge.

of said side wall, and an insulating strip applied over the edge of said disks and sealing the joints therebetween substantially as described.

- 5 6. A shipping case comprising two members one of which is adapted to telescopically fit over the other, each member being provided with insulation in its side walls, and with double insulation in its end walls, the outer member being provided with a cover of water-proof material and the inner member with a lining of salt-resistant material, and an apron secured to the outer side of the inner member, and sealing
- 10

the space between said members substantially as described. 15

7. A shipping case comprising two members one of which is adapted to telescopically fit over the other, each member being provided with a closed end wall, and with insulating material incorporated in the side wall and end wall, the insulating efficiency of said end wall being double the insulating efficiency of the said side wall. 20

In testimony whereof we affix our signatures. 25
